J. W. OSBORNE

RAILROAD SIGNAL

Filed March 15, 1923

UNITED STATES PATENT OFFICE.

JOHN W. OSBORNE, OF WINCHESTER, ILLINOIS, ASSIGNOR OF ONE-HALF TO HENRY C. SIX.

RAILROAD SIGNAL.

Application filed March 15, 1923. Serial No. 625,322.

To all whom it may concern:

Be it known that I, JOHN W. OSBORNE, a citizen of the United States, residing at Winchester, in the county of Scott and State of Illinois, have invented certain new and useful Improvements in Railroad Signals; and I do declare the following to be a full, clear, and exact description of the invention, such as will enable others skilled in the art 10 to which it appertains to make and use the same.

This invention relates broadly to improvements in railroad signals of the type employed at highway crossings to warn approaching pedestrians and automobile drivers of forthcoming danger, but the invention has more specific reference to a unique sound producing device for use in connection with such signal.

20 The principal object of the invention is to provide a unique sound producing device for use in connection with signals of the above types wherein automatically controlled means is employed for producing 25 air currents in a sound amplifying chamber wherein a novel vibrating medium is contained to be acted on by the incoming air.

More specifically, it is another object of the invention to provide a train controlled 30 electrical device for automatically driving a bladed rotor which serves to create a strong air current for acting on the vibrating medium located in the sound amplifying chamber.

35 Other objects and advantages of the invention will be apparent during the course of the following description.

In the accompanying drawings forming a part of this specification and in which like 40 numerals are employed to designate like parts throughout the same:

Figure 1 is a view showing a perspective view of a portion of a railroad track with the circuit closing means associated therewith and the improved signal device (in side elevation) with which the circuit wires are connected.

Figure 2 is an enlarged vertical section, with parts in elevation, through the improved sound producing device.

Figures 3 and 4 are enlarged cross sections taken on the line 3—3 of Fig. 2 looking in opposite directions respectively.

Before proceeding with the detailed description of the invention, I wish to point

out that the novelty of the present invention resides more or less, as before indicated, in the provision of unique sound producing means which is especially, but not necessarily adapted to be used in connection with automatically operable means such as employed in the well known type of railroad signals used at highway crossings to warn automobilists and pedestrians of approaching danger. In view of the fact that the improved device was originally designed for use in connection with railroad signals, I have associated it with such a signal in the drawings. It is to be understood however that the unique sound producing means can be used in connection with various other forms of signals.

In the drawings, the letter R designates generally portions of a railroad track with one rail of which an angle iron I is associated. This iron is spring-pressed as is shown so that after it is depressed by the train, it will be automatically returned to its normal position. As usual, this depressible iron carries one element of a suitable form of switch S and the usual wires are connected with these switch elements so that the circuit will be completed when the switch is closed. It is of course understood that the switch is not closed until the wheels of the train run over the angle iron and depress it a predetermined degree. The wires W are connected with batteries placed in a concrete box or the like B which is preferably embedded in the ground G below the surface thereof to guard against freezing of the batteries.

The foregoing details are old and well known and constitute no part of the present invention which, as before indicated, resides in the provision of a unique sound producing device for use in connection with the foregoing details. Although, the improved device could be of some other construction, it preferably comprises a vertical tubular standard 1, on the upper end of which a substantially oblong casing 2 is mounted. Arranged within the casing is a partition 3 which divides the casing into compartments 4 and 5. Arranged in the compartment 5 is an electric motor 6 which serves to drive a bladed rotor 7 which is housed within the other compartment 4. The last named compartment may be conveniently designated hereinafter as an amplifying chamber for

the sound waves introduced into this chamber when the device is in action as will hereinafter become obvious. The compartment 5 is formed at one end with an air discharge opening 8 and the compartment 4 is provided at the center of its removable closing plate 9 with a relatively large intake opening and in order to permit the air to pass from one compartment into the other, the 10 partition is provided with one or more apertures at suitable points. For introducing a comparatively large quantity of air into the chamber 4, I employ a horn 10 which has its constricted end arranged in the intake opening 15 in the closing plate 9. So that the incoming air will produce audible sound waves, I provide a unique vibrating means which preferably comprises a series of metal tongues or reeds 11 arranged in openings 20 formed in a carrying plate 12 bolted or otherwise secured to the inner face of the closing plate 9 to dispose the vibrating elements 11 at the same end of the horn. Although it is not essential, I prefer to employ 25 in conjunction with the aforesaid details, a second horn 13 and I connect this horn with the sound amplifying chamber 4 at any suitable point. It is yet to be pointed out that suitable wires are of course connected with 30 the aforesaid batteries and these lead to the motor 6 to supply current thereto for driving the bladed rotor.

From the foregoing, it is obvious that when the angle iron 1 is depressed by the 35 wheels of a passing train, the switch S will be closed and a circuit will be completed to set the rotor 7 into rotation. As the rotor revolves rapidly, it will suck air through the large horn 10 into the compartment 4 and as the vibrating elements 11 are disposed at the constricted end of this horn, it will be obvious that these will be freely vibrated to produce audible sound waves which will be considerably amplified in the chamber 4 and discharged through the small horn 13 in the form of audible sounds which will be of sufficient intensity to be heard at a considerable distance by automobile drivers and 45 pedestrians approaching the railroad crossing. Hence, they will be warned of an approaching train and can protect themselves against injury at the crossing track while in danger.

To add to the effectiveness of the device, I 50 contemplate arranging a small dome D on top of the casing 2 and in this dome I place an electric bulb which is simultaneously

lighted when the audible signal is actuated and is rendered visible through the glass wall of the dome. Also, if desired, a stop 60 sign A may be mounted on top of the dome. Hence, the stop sign will serve in the daytime to indicate the approach of a railroad crossing and the light will serve at night.

By carefully considering the description 65 in connection with the drawings, persons familiar with devices of this class will doubtless be able to obtain a clear understanding of the invention. Therefore, a more lengthy and detailed description is deemed unnecessary.

Since probably the best results may be obtained with the construction and arrangement herein shown and described, this is taken as the preferred embodiment of the 75 invention. However, I wish it to be understood that minor changes coming within the scope of the invention as claimed, may be resorted to if desired.

I claim:

1. In an audible signal, a tapered air intake passage, a vibrating medium located at the small end of the passage, and automatically operated means spaced in back of said vibrating medium for producing a suction 85 in the passage to direct currents of air against the vibrating medium.

2. In an audible signal, a casing, an air intake connected thereto, vibrating elements in the casing in the path of the air, and a 90 rotor in the casing for drawing air into it and against the vibrating elements.

3. An automatically operable audible signal comprising a casing having air intake and discharge openings, an outwardly flared 95 horn connected to said intake, a bladed rotor in the casing in horizontal alignment with the axis of the horn, and vibrating elements located in the path of the air.

4. An automatically operable audible signal comprising an elongated casing having openings in its ends, a flared air intake horn connected with one of said openings, vibrating means at the inner end of said horn, a partition dividing said casing into separate 105 compartments, a motor in one compartment and a rotor driven thereby and arranged in the other compartment for co-action with said vibrating means, and a sound emitting and amplifying horn leading from said last 110 named compartment.

In testimony whereof I have hereunto affixed my signature.

JOHN W. OSBORNE.
